UNITED STATES PATENT OFFICE.

OLIVER F. MITCHELL, OF MERRILL, WISCONSIN, ASSIGNOR OF ONE-HALF
TO WILLIAM H. SWINEHART, OF SAME PLACE.

TABLE-LEG.

SPECIFICATION forming part of Letters Patent No. 321,907, dated July 7, 1885.

Application filed February 5, 1885. (No model.)

To all whom it may concern:

Be it known that I, OLIVER F. MITCHELL, a citizen of the United States, residing at Merrill, Lincoln county, Wisconsin, have invented new and useful Improvements in 5 Table-Legs, of which the following is a specification.

In the use of some kinds of tables it is required that they be exactly level, any unevenness or inequality of level destroying their usefulness. This is especially the case with that 10 class of tables typically known as "billiard-tables."

Such tables as now ordinarily constructed 15 are made with slate or marble beds, the beds consisting of several sections carefully trued and joined at their edges. To properly level 20 and adjust such tables without disturbing the joints or lines of union of the sections of the bed is a tedious operation, requiring care and patience.

The object of my invention, therefore, is to furnish means by which said tables may be 25 readily leveled and adjusted, while the danger of disturbance of the sections at their lines of union is reduced to a minimum. In order to accomplish this, I form a recess at the top of the leg, open on its two interior sides, but bounded on the two outer or visible sides by 30 walls forming portions of the leg, while the bottom of the leg is recessed to receive a nut. An aperture is formed longitudinally through the leg from the top to bottom recess, through 35 which is to pass a bolt. To this bolt is attached a head concealed within the upper recess, while the lower end of the bolt is screw-threaded and passes through a nut in the lower recess, the length of the bolt being such that its lower end passes beyond the lower end of 40 the leg. From this it will be readily understood that if, by means of the head in the upper recess, the bolt be turned, it will, through its coaction with the nut in the lower recess, raise or lower, as the case may be, the table resting 45 upon the upper end of the leg.

In practice, in order to prevent any slipping or lateral movement, I prefer that the lower end of the bolt shall rest upon a bed having upon its under side projections or a roughened

surface. This construction may be more readily understood by reference to the drawings, in which—

Figure 1 is a side view of a table-leg embodying my invention, taken from the inner side. Fig. 2 is a longitudinal section of the 55 same in a position beneath a table. Fig. 3 is a top view of the leg; Fig. 4, a plan view of the foot for the leg.

The reference-numeral 1 indicates the body of the leg, at the top of which is formed a recess, 2, open on two sides but bounded on the other two sides by walls 3, forming part 60 of the leg. From this recess an aperture passes longitudinally through the leg to a lower recess, 10, of a size and shape to receive a nut, 65 7. A bolt, 4, having a head, 5, of a shape to afford means for manipulation with a wrench, passes through the aperture in the leg, and has its lower end screw-threaded, as at 6, to engage with the nut 7. The leg supports the table 11 70 upon the walls 3 of its recess, these walls being on the outer or visible sides of the table, so that the recess 2 is concealed, the leg being joined to the table by dowels or pins 12, or in 75 any other suitable way. It follows that whenever it is desired to level a table provided with legs of this construction it is only necessary, in order to cause the necessary variation in the height of the bed or base, to simply turn, through the medium of the head 5, the bolt 4, 80 which thereupon is projected (more or less, as the case may be) beyond the nut 7, the bearing of the legs 1 and table upon the floor being only through the bolt 4 and nut 7.

In order to give a firm bearing for the end 85 of the bolt, and to prevent lateral movement or displacement, I prefer to use a foot, 8, therewith. This foot is preferably of cast-iron, although it may be of any desired material. It is formed with a slight depression or concavity, 13, in which rests the end of the bolt 4, 90 while its under side is roughened or is provided with a few small teeth or projections, 9 9, which taking into the floor render lateral movement impossible. It is of course to be 95 understood that all the legs of a table which is desired to be level and kept level are to be of this construction. If they are so, the level-

ing becomes a comparatively easy and simple matter, as the smallest possible variations are attainable by the use of the screw-bolt without any jar to the table itself, and changes of level of any side or part may be made so gradually and easily as to obviate the danger of starting any of the bed-joints or destroying the absolute and necessary accuracy of the union of the bed-sections.

I am aware that various screw devices have been used in connection with table-legs for the purpose of leveling the table. For instance, a two-part leg has been used, with a screw passed through the upper section into and terminating within the lower section, said screw being provided with a head having sockets for the insertion of a tool from the outside of the leg to turn the screw. In this form a space is formed between the two sections of the leg when an adjustment is effected. There has also been used a screw passed through the body of the table and the leg, provided at its lower end with an adjusting-nut. In such form the table must either first be lifted before turning the nut, or else the nut be turned while in contact with the floor. There has also been applied a nut with projections on its side to the screw-threaded end of the leg, the nut having a bearing on the inside of a socket-plate resting upon the floor.

My invention differs from said several constructions in having a single bolt passed en-

tirely through the leg, access being had to the head of the bolt at the upper end of the leg, and a nut being applied to the threaded end 35 of the bolt inside of the lower end of the leg and the lower end of the bolt resting upon a plate, whereby the construction is made very simple, and the adjustment can be effected without the necessity of first lifting the table 40 and without injury to the floor.

Having thus described my invention, what I claim is—

1. The combination of a table-leg having recesses, one each at its top and bottom, the top recess opening at the side of the leg, an aperture connecting the recesses, a threaded bolt passing through said aperture, a nut applied to said bolt within the lower recesses of the leg, and a plate having projections on its lower face and a concavity in its upper face for the end of the bolt to rest in, substantially as described.

2. A table-leg consisting of the solid body 1, having recesses 2 6, connected by an aperture, 55 the bolt 4, having head 5, and the nut 7, substantially as described.

In testimony whereof I affix my signature in presence of two witnesses.

OLIVER F. MITCHELL.
